UNITED STATES PATENT OFFICE

GEORGE S. MAYNARD, OF NEWTONVILLE, MASSACHUSETTS, ASSIGNOR TO UNITED-CARR FASTENER CORPORATION, OF CAMBRIDGE, MASSACHUSETTS, A CORPORATION OF MASSACHUSETTS

PIN FASTENER

Application filed December 2, 1930. Serial No. 499,474.

My invention aims to provide improvements in pin fasteners particularly, though not exclusively useful in connection with the attachment of slip covers to upholstery.

5 In the drawings which illustrate a preferred embodiment of my invention:

Figure 1 is an elevation view of my pin fastener as it appears when securing a slip cover in position;

10 Fig. 2 is an enlarged section taken on the line 2—2 of Figure 1;

Fig. 3 is an elevation view of the pin fastener per se;

15 Fig. 4 is a section taken on the line 4—4 of Fig. 3 showing the hinged plate in unlocked position; and

Fig. 5 is a rear elevation of the pin fastener shown in Fig. 3.

The pin fastener illustrated by the drawings is an improvement over the well known type of "campaign" button fastener which has been used to a large extent in securing slip covers to upholstery. That type of fastener has been objectionable because it would 20 pull loose or if provided with means to prevent pulling loose then it could be removed only with difficulty and in many cases resulted in injury to finger nails and/or to the material to which they were attached.

25 30 My improved fastener is easy to attach and detach and is securely locked in place in a very simple and effective manner without injury to the material during attachment or detachment.

35 The particular device selected for illustration comprises an attaching part 1 and a plate part 2. The attaching part 1 is made of wire and has two parallel sharp pointed legs 3 connected by a portion 4 having a bend 5 formed therein and extending between and in the same direction as the legs 3, as best shown in Figs. 1 and 5. The plate part 2 has 40 hinges 6 (Fig. 5) engaging the connecting portion 4 at opposite sides of the bend 5, so that the plate part may swing relative to the attaching portion for purposes hereinafter described. Furthermore, the plate part 2 has 45 a yieldable finger 7 extending from the lower end of the plate part upwardly for a distance substantially parallel to and underly-

ing the plate part, as shown in Figs. 2 and 5. This finger 7 then extends rearwardly from the plate part 2 to provide a sharp pointed prong portion 8. The prong portion 8 is bent slightly so that the finger 7 may be forced to yield when the prong portion engages the bend 5 during the attaching operation.

To attach the fastener to a structure such as that shown in Fig. 2, the plate is swung into a position substantially at right angles to the legs 3. Then with the plate part 2 grasped between the thumb and the first and second fingers the sharp pointed legs 4 may be easily forced through the slip cover 9 and into embedded relation with the upholstery 60 65 10. Thereafter the plate part 2 is pressed toward the slip cover 9 and the prong portion 8 of the yieldable finger 7 is forced through the slip cover 9 and into the upholstery, as shown in Fig. 2, thereby securely 70 fixing the fastener against accidental withdrawal. During the latter part of the attaching operation the prong portion 8 engages the bend 5 (Fig. 4) and the bend acts as a cam to spring the finger 7 so that when 75 the plate part is pressed against the slip cover the flattened end of the bend 5 will engage the depression 11 formed in the finger. Thus the plate 2 is securely locked in position and cannot accidentally be brushed into unlock- 80 ing position.

When the fastener is attached as above described the slip cover 9 is held securely in position and the prong portion 8 prevents the legs 3 from pulling out of the upholstery 85 90 when lateral stress is exerted upon the slip cover 9. To remove the fastener it is merely necessary to lift the lower edge of the plate part 2 thereby pulling the prong portion 8 from the installation. Then the plate part 2 90 may be grasped and the pin removed by exerting an upward pull thereon.

My invention is equally useful in connection with snap fastener secured installations of a slip cover by providing the plate part 95 2 with a socket or a stud and securing it to the upholstery 10 beneath the slip cover 9 and attaching a cooperating snap fastener element to the slip cover, all of which is well known to those skilled in the art.

While I have illustrated and described a preferred embodiment of my invention I do not wish to be limited thereby, because the scope of my invention is best defined by the 5 following claims.

Claims:

1. A pin fastener comprising, in combination, an attaching part, an imperforate plate part formed from a single piece of metal and 10 hinged to said attaching part, a yieldable stabbing prong formed integral with and extending from said plate part, said prong being located inwardly a substantial distance from the edge of the plate part and being 15 concealed by said plate part and a prong-engaging portion provided by said attaching part for cooperation with said prong to lock said plate part in a given relation to said attaching part.

20 2. A pin fastener comprising, in combination, an attaching part, an imperforate plate part formed from a single piece of metal and hinged to said attaching part, a pair of spaced sharp pointed legs provided by said attaching member, a finger formed integral with and extending from said plate part and a cam portion provided by said attaching member between said legs and adapted to cooperate with said yieldable finger to lock said 25 plate part in a given relation to said attaching part.

25 3. A double pointed pin fastener comprising a wire part 1 and a plate part 2, the wire part 1 having two sharp pointed legs 3 connected by a portion 4 having a bend 5 located between the legs 3, a flat portion provided at the end of said bend thereby providing a substantial bearing surface, hinges 6 provided by the plate part 2 and engaging the connecting 40 portion 4, a yieldable finger 7 located beneath the plate part 2 and having a sharp pointed prong 8 extending from said finger for engagement with the medium to which the fastener is to be attached to lock it in place 45 and for engagement with the flat bearing surface of the bend 5 to lock the plate part 2 in a given relation to the attaching part 1.

4. In a pin fastener, a double pronged pin having a cross bar connecting its prongs, 50 said cross bar provided with a loop, a cap hinged to said cross bar intermediate said pin prongs and overlying and concealing said loop and provided with a prong engageable with the material to which the pin fastener is applied, and said cap carrying a snap fastening element engageable with said loop to detachably lock said cap and its prong in fixed relation to said pin.

5. In a pin fastener, a double pronged pin 60 having a cross bar connecting its prongs, said cross bar provided with a loop, a unitary cap structure hinged to said cross bar intermediate said pin prongs and loop and including a prong engageable with the material to which the pin fastener is applied and a snap fasten-

ing element engageable with said loop to detachably lock said cap and its prong in fixed relation to said pin.

In testimony whereof, I have signed my name to this specification.

GEORGE S. MAYNARD.
